UNITED STATES PATENT OFFICE.

FREDERICK J. RODE, RALPH I. FROST, AND JOHN L. LISTON, OF AUGUSTA, KANSAS;
SAID RODE AND SAID FROST ASSIGNORS TO SAID LISTON.

SIGNAL LANTERN.

Application filed April 21, 1921. Serial No. 463,191.

To all whom it may concern:

Be it known that we, FREDERICK J. RODE, RALPH I. FROST, and JOHN L. LISTON, citizens of the United States, residing at Augusta, in the county of Butler and State of Kansas, have invented a certain new and useful Improvement in Signal Lanterns, of which the following is a specification.

Our invention relates to improvements in signal lanterns.

The object of our invention is to provide a signal lantern with which any one of a plurality of different colored lights may be projected.

15 A further object of our invention is to provide a novel lantern of the kind described, which is simple in construction, cheap to make, not liable to get out of order, durable, and with which the signals can be 20 quickly changed.

Our invention provides still further a construction in which new lamps may be quickly substituted for those which have been burned out.

25 Our invention provides still further a lantern carrying two batteries and a plurality of electric lamps combined with means by which the lamps may be placed in circuit with either of the batteries.

30 The novel features of our invention are hereinafter fully described and claimed.

In the accompanying drawings, which illustrate the preferred embodiment of our invention,

35 Fig. 1 is a vertical sectional view, partly broken away on the line 1—1 of Fig. 2, showing our improved signal lantern.

Fig. 2 is a sectional view on the line 2—2 of Fig. 1, some of the parts being shown in 40 plan.

Fig. 3 is an enlarged vertical sectional view on the line 3—3 of Fig. 2.

Fig. 4 is a vertical sectional view on the line 4—4 of Fig. 2.

45 Fig. 5 is a diagrammatic view of the electric circuit in which the lamps are located.

Similar reference characters designate similar parts in the different views.

1 designates an inverted cup-shaped casing provided in its top with an opening 2, and having removably fitted in its lower end a cap or base member 3, which supports two batteries 4 and 5, mounted on spring plates 6, which bear against the lower ends of the 55 batteries, said lower ends constituting one

set of terminals, the upper terminals, 7, of which bear respectively against two contact plates 8, mounted respectively on two blocks 9 of insulation, which are respectively secured to two vertical partitions 10 and 11, 60 extending across the casing 1 and spaced apart from each other above the base member 3.

Extending horizontally through the casing 1 is a central manually rotatable shaft 65 12, having secured to one outer end a thumb button 13, Fig. 2.

The shaft 12 extends through the partitions 10 and 11, and has rigidly secured to it a rotary device of conducting material provided with peripheral lamp receiving sockets and consisting, preferably, of a circular plate of metal 14, to one side of which is secured an annular plate 15, which is provided with radial semi-circular grooves 16, respectively registering with similar radial grooves 17, on the adjacent side of the plate 14.

A cylindrical member 18 of insulating material is mounted on the shaft 12, and is encircled by the plate 15, and is attached by 80 screws 19 to the plate 14.

The periphery of the member 18 is provided with a plurality of longitudinal equally spaced curved grooves 20, each of which is adapted to have rest in it the free 85 end of a spring plate 21, of conducting material, which has its other end rigidly secured to a block of insulating material 22, which is secured to the partition 11. The plate 21 serves to hold the member 18 and 90 with it the lamp supporting device from accidental turning from the position to which it may be adjusted.

A plurality of spring contact members 23, are mounted respectively in alternate ones of the recesses 20 and are secured by screws 24, Fig. 2, to the insulating member 18.

A plurality of electric lamps 25, which may be provided respectively with different colored glass bulbs, each of which is mounted 100 in a sleeve 26 of conductive material and which forms one of the terminals of the lamp, the other terminal of which, designated by 27, is disposed centrally at the inner end of the lamp. The sleeves 26 are respectively removably fitted in the sockets formed by the radial grooves 16 and 17 in the plates 14 and 15 respectively, and when mounted in their operative positions, the terminals 27 respectively bear upon the contact members 23. 110

The arrangement is such that as the thumb button 13 is turned so as to rotate the plates 14 and 15 and member 18, the lamps 25 will be consecutively extended through the opening 2, all the lamps but the one so extended being cut out of circuit with the battery 4 or 5 as the case may be. The lamp 25 which is extended through the opening 2 in the position occupied by the uppermost lamp in Fig. 10 1, will be in circuit with the battery which is at the time connected with the spring circuit closer 21, and the light projected will depend upon the color of the glass bulb of the lamp. The member 21, while serving to 15 close the circuit through the adjacent lamp by means of its contact with the adjacent contact member 23, also serves to hold the member 18 and plates 14 and 15 from axial turning. If the button 13 is rotated a complete 20 rotation, the lamps 25 will be consecutively lighted, so that different signals may be displayed. If the member 18 is stopped in its rotation at points where the spring member 21 enters the recesses 20 which are intermediate of those containing the contacts 23, all 25 the lamps will be cut out of circuit with the battery, and the member 18 will be held from accidental turning.

For connecting the spring contact member 30 21 in circuit with either battery 4 or 5, we provide a switch comprising the following described parts.

Extending through and rotatable in the side wall of the casing 1 is a member 28, of 35 insulating material and having secured to its outer end a crank 29. To the inner end of the member 28 is secured a metal plate 30, which is connected by a conducting wire 31 with the circuit closing member 21. The 40 plate 30 is adapted to electrically engage either one of two contacts 32 and 33, which are mounted on insulating member 34, which is secured to the inner side of the casing 1. The contacts 32 and 33 are respectively connected 45 by conductors 35 and 36 with pins 37 and 38 respectively mounted in the blocks 9 and respectively connected electrically with the plates 8.

The casing 1, base member 3 and partition 50 10 are of conductive material and serve as a ground for the electric circuit. The bottom of each battery 4 and 5 forms one terminal of the battery which is connected to the base 3 or ground by the springs 6. The sleeves 26 55 are connected to ground by the plate 14, through the intervention of a spring plate 39 secured to the plate 14 and bearing against the partition 10.

Referring to Fig. 5, 40 designates conductors representing the plates 14 and 39, which connect the sleeves 26 to ground.

With the switch plate 30 in contact with the contact 32, as shown in Fig. 5, the current from the battery 5 will pass from the 65 terminal 7 through the adjacent plate 8, pin

37, conductor 35, contact 32, plate 30, conductor 31, and circuit closing member 21, to the contact member 23, then engaged by the member 21, thence through the adjacent terminals 27 and 26, and thence to ground 70 through the conductor 40, and from ground back to the battery 5, through the adjacent spring plate 6. The uppermost lamp, which is then in circuit with the circuit closing member 21 will be lighted, thus giving the 75 signal desired. By turning the thumb button 13, as before described, the different contacts 23 may be brought into engagement with the member 21, so as to have the lantern show the different signals. 80

When the battery 5 becomes exhausted, or weak, the crank arm 29 is turned to a position in which the plate 30 will engage the contact 33, upon which the current will pass from the battery 4 through the adjacent terminal 7 and adjacent plate 8, pin 38, conductor 36, and contact 33, to the plate 30, and thence to ground in the manner already described, and from thence back to battery 4, through the adjacent spring plate 6. 90

When it is desired to replace a battery, the base 3 is removed from the casing 1.

For holding each lamp 25 in its socket, it is provided with the usual securing means consisting of two diametrically opposite pins 95 41, arranged to respectively enter the slots 42, Fig. 1, extending radially from the peripheries of the plates 14 and 16, each slot having at its inner end a right angled turn. In inserting a lamp, the pins 41 are slipped 100 into the oppositely disposed slots 42 to a position in which the terminal 27 will compress the adjacent spring contact member 23, upon which the lamp is turned in its socket, so that the pins 41 enter the offsets at the inner ends 105 of the slots 42.

The top of the casing 1 is provided with an annular groove 43, which encircles the opening 2, and in which is fitted the lower end of a glass chimney 44, upon the upper end of which is provided a cap 45, Fig. 1, which is vertically slidable on a vertical pin 46, the upper end of which is centrally attached to a top plate 47, the periphery of which is adapted to be fitted into two recesses 48 provided on the inner sides respectively of the two vertical arms of an inverted U-shaped handle 49, the lower ends of the arms being respectively attached to opposite sides of the casing 1. 110

Clamped between the pin 46 and top 47, is a spring plate 50 which bears against the cap 45, and holds the latter upon the chimney 44. The lower end of the pin 46 is screw-threaded and has mounted on it a nut 51, which holds the cap 45 from sliding off the pin, when the chimney 44 is removed. 115

In the operation of our invention, the thumb button 13 is turned so as to bring 120

the lamp having the desired color to be displayed into the longitudinal center of the chimney 44. The member 21 will hold the lamp in this position and will supply it with current from the battery. When it is desired to display no light, the thumb button 13 is turned so as to bring the member 21 into one of the recesses 20, which is not occupied by a contact member 23. In this position, the battery circuit will be broken, and the members 18 and 14 and 15 will be held from rotation.

By having the lamp located in alternate recesses 20, any lamp can be extinguished without lighting any other lamp, and the lamps will be reliably held in the extinguished position by the contact member 21 being disposed in one of the intermediate recesses 20.

By having the batteries in the base, below the shaft 12 and having the lamp displayed above the base, a maximum range of illumination is afforded, and the center of gravity of the lamp is lowered, thus affording stability when the lamp is resting on its base.

We do not limit our invention to the structure shown and described, as many modifications, within the scope of the appended claims, may be made without departing from the spirit of our invention.

What we claim is:—

1. In a lantern of the kind described, a rotary conducting device having peripheral sockets, an insulating member rotatable with said device and having a plurality of peripheral recesses, contacts mounted respectively in alternate ones of said recesses, a support on which said rotary device and insulating member are mounted, a spring circuit closing member mounted on said support and arranged to consecutively enter said recesses and to engage said contacts, and a plurality of electric lamps respectively mounted in said sockets and having two sets of terminals, one set of which is in contact with said rotary device, and the other terminals of which respectively engage said contacts, a battery carried by said support, and conducting means for connect-

ing said battery in circuit with said rotary device and said circuit closing member, substantially as set forth.

2. In a lantern of the kind described, a support, two batteries, independent of one another, carried thereby, a circuit closing member, a plurality of electric lamps having two sets of terminals, conducting means connecting said batteries, with one set of terminals, means by which the other terminals are adapted to be consecutively connected with said circuit closing member, and conducting means including a switch connected with said circuit closing member and by which the latter may be connected in circuit with either one of said batteries, substantially as set forth.

3. In a lantern of the kind described, a hollow base having an opening in the top, a transparent globe mounted on the base and encircling said opening, a battery in said base, a manually rotated member mounted in said base with its axis above said battery, a plurality of electric lamps carried by said rotary member and arranged when the latter is rotated, to be consecutively extended through said opening, and means in circuit with said battery by which said lamps will be consecutively connected with said battery so as to become active as they are consecutively extended through said opening, substantially as set forth.

4. In a lantern of the kind described, a support, an insulating rotary member mounted on said support, peripheral contacts on said rotary member, two plates fastened together side by side, one being conductive and both rotatable on said support with said rotary member, said plates having on adjacent sides radial grooves co-operating to form lamp sockets, said sockets being in radial alinement respectively and adjacent to said peripheral contacts substantially as set forth.

In testimony whereof we have signed our names to this specification.

FREDERICK J. RODE.
RALPH I. FROST.
JOHN L. LISTON.
